UNITED STATES PATENT OFFICE

144,301

DESIGN FOR A REEL FOR TAPE CORES

Harry Preble, Jr., New York, N. Y., assignor to
International Plastic Corporation, Morristown,
N. J., a corporation of Illinois

Application October 6, 1945, Serial No. 122,609

Term of patent 14 years

(Cl. D74—1)

To all whom it may concern:

Be it known that I, Harry Preble, Jr., a citizen of the United States, residing at New York, in the county of New York and State of New York, have invented a new, original, and ornamental Design for a Reel for Tape Cores, of which the following is a specification, reference being had to the accompanying drawing, forming a part thereof.

In the drawing:

Figure 1 is a front elevational view of a reel for tape cores embodying my design; and
Figure 2 is a side view thereof.

I claim:

The ornamental design for a reel for tape cores, substantially as shown.

HARRY PREBLE, JR.
